UNITED STATES PATENT OFFICE.

THOMAS O. ADAMS, OF NEW PHILADELPHIA, OHIO, ASSIGNEE TO THE WISE-McCLUNG MANUFACTURING COMPANY, OF NEW PHILADELPHIA, OHIO, A CORPORATION OF OHIO.

ADJUSTABLE BRUSH FOR VACUUM CLEANERS.

Application filed October 9, 1922. Serial No. 593,842.

To all whom it may concern:

Be it known that I, THOMAS O. ADAMS, a citizen of the United States, residing at New Philadelphia, in the county of Tuscarawas and State of Ohio, have invented a new and useful Adjustable Brush for Vacuum Cleaners, of which the following is a specification.

This invention relates to brushes for suction cleaning nozzles and more particularly to an adjustable brush mounted upon the outside of the nozzle adjacent to the lip thereof, and arranged to be detached from the nozzle or moved out of engagement with the carpet or other surface to be cleaned.

15 The objects of the invention are to provide a cleaning nozzle with an unobstructed opening, a brush being detachably mounted upon the outside of the nozzle adjacent to the lip thereof, and arranged to be easily 20 and readily moved into inoperative position out of engagement with the carpet or surface to be cleaned.

The above and other objects may be attained by constructing the nozzle and brush 25 as illustrated in the accompanying drawings, in which—

Figure 1 is a side elevation of a vacuum cleaner, the nozzle portion being shown in section, the brush being located in the operative position;

Fig. 2, a sectional view of the nozzle showing the brush in the inoperative position;

Fig. 3, an inverted, perspective view of the 30 nozzle with the brush detached;

Fig. 4, a sectional view of the brush, showing the means of attaching the same to the nozzle;

Fig. 5, an inverted, perspective view of an 40 attachment nozzle showing the brush attached thereto;

Fig. 6, a detached, perspective view of the brush shown in Fig. 5; and

Fig. 7, a sectional view of one of the 45 brushes shown in Figs. 5 and 6.

Similar numerals refer to similar parts throughout the figures of the drawings.

The cleaner shown in Figs. 1 to 4, includes the motor casing 1, fan casing 2 and nozzle 50 3, mounted for to and fro movement upon the floor upon the front and rear castors 4 and 5 respectively, the handle bail 6 being pivotally connected to the motor casing and for the reception of an operating handle by

means of which the cleaner may be manipulated upon the floor. 55

For the purpose of taking up from a carpet, or other surface to be cleaned, thread, lint or similar loose material, it is desirable to provide the nozzle with a disturbing device, such as a brush, to engage and loosen the threads or other material from the surface being cleaned, such disturbing device being desirably located outside of the nozzle 60 in order that an unobstructed nozzle opening be provided.

The disturbing device illustrated in Figs. 1 to 4 inclusive of the drawings, comprises a straight brush 7 parallel with and in rear of the rear lip 8 of the mouth of the nozzle. 70 This brush is mounted upon a tubular rod 9 carried upon brackets 10 mounted near each end portion of the nozzle, one of said brackets having a stud 11 and the other bracket having a similar stud 12 provided 75 with a transverse pin 13, the extremities of which stand beyond opposite sides of the studs.

A coil spring 14 is located within one end of the tube 9 and arranged to engage the 80 end of the stud 11 when the tube is inserted over said stud, as shown in Fig. 4, the other end of the tube being notched upon diametrically opposite sides, as shown at 15, to engage the extremities of the pin 13. 85

With this construction, the brush may be rigidly held in the operative position, as shown in Fig. 1, by engagement of the notches 15 with the extremities of the pin 13, or the brush may be reversed and held in the 90 raised position, as shown in Fig. 2, the notches engaging the opposite ends of the pin 13. If for any reason it is desired to remove the brush from the nozzle, the same may be accomplished by pressing the brush longitudinally toward the stud 11, compressing the spring 14 until the opposite end of the tube 9 is released from the stud 12, when the entire brush may be detached from the nozzle. 100

In adjusting the brush to either of the positions shown in Figs. 1 or 2, it is only necessary to press the brush longitudinally against the stud 11 until the notches 15 are disengaged from the stud 12, when the brush 105 may be rotated upon its axis to the opposite position, the notches 15 being again engaged with the pin 13.

Referring now to the construction illustrated in Figs. 5 to 7 inclusive, an attachment nozzle for cleaning draperies, upholstering and the like is illustrated at 16, an attaching plate 17 being connected to each end of the nozzle as by a screw 18, the ends of said attaching plate extending outward upon both sides of the nozzle.

Each of the plates 17 has an inwardly disposed stud 11^a at one end and a similar stud 12^a at the other end, provided with a transverse pin 13^a extending diametrically through the stud and projecting outward upon opposite sides of the stud. Each of the 15 brushes 7^a is mounted upon a tube 9^a, one end of which contains a coil spring 14^a arranged to engage the adjacent stud 11^a, the opposite end thereof being provided with diametrically opposite notches 15^a arranged 20 to engage the adjacent pin 13^a.

The operation of the brushes 7^a is the same as the operation of the brush 7 above described, each brush being arranged to be held fixedly in the operative position as 25 shown in Fig. 5, or in the inoperative position, out of engagement with the surface to be cleaned. These brushes, the same as the brush 7, may be easily detached from the nozzle in the manner above described.

30 It is pointed out that each of the brushes 7^a has bristles extending from one end to a point slightly spaced from the opposite end and as the two brushes are located in reversed position with reference to each other, 35 as best shown in Fig. 5, bristles are provided along the entire length of the mouth of the nozzle.

I claim:—

1. The combination with a suction cleaning nozzle having lips for contact with the surface to be cleaned, of a rotatable rod 40 mounted parallel to one of said lips, a brush upon said rod, locking means for holding the brush in the operative or inoperative position, and means for sliding the rod longitudinally to disengage the locking means.

2. The combination with a suction cleaning nozzle having lips for contact with the surface to be cleaned, of a rotatable rod 50 mounted parallel to one of said lips, a brush upon said rod, locking means for holding the brush in the operative or inoperative position, and means for sliding the rod longitudinally to disengage the locking means, and a spring for normally holding the rod in 55 locked position.

3. The combination with a suction cleaning nozzle having lips for contact with the surface to be cleaned, of a rotatable rod 60 mounted parallel to one of said lips, a brush upon said rod, a pin upon the nozzle, notches at one end of the rod for engagement with the pin and a spring for normally holding the notches in engagement with the pin.

4. The combination with a suction cleaning nozzle having lips for contact with the surface to be cleaned, of a pair of aligned studs near opposite ends of one lip, a tube journaled upon said studs, a pin in one of the studs, notches in the adjacent end of 70 the tube, a spring at the opposite end of the tube for holding the notches in engagement with the pin and a brush upon said tube.

THOMAS O. ADAMS.
